UNITED STATES PATENT OFFICE

2,291,655

DOORKNOB FASTENER

Walter R. Schlage, Burlingame, Calif., assignor
to Schlage Lock Company, San Francisco,
Calif., a corporation of California

Application March 12, 1941, Serial No. 382,878

2 Claims. (CL 292—352)

This invention relates to a door knob fastener, and especially to a modified form of the fastener disclosed in my former Patent No. 2,007,350, entitled "Demountable knob and cylinder lock," issued July 9, 1935.

In the above mentioned patent, a knob fastener is disclosed which is adapted to be locked or dogged by a key mechanism mounted in the outer knob to prevent removal of the knob except by an authorized person who has possession of the proper key. The present patent discloses a knob fastener which is applicable to both the inner and the outer knob, and which is adapted to be dogged or locked by key-actuated means in the outer knob, and by manually actuated means in the inner knob; and further, to provide a knob fastener which is actuated by a spring and a detent, and in which the spring and detent also function to yieldingly retain the manual member in one or more of a number of predetermined positions.

The invention is shown by way of illustration in the accompanying drawings, in which:

Fig. 1 is a horizontal section of a door lock, showing it mounted in a door;

Fig. 2 is a section similar to Fig. 1 showing the dogging members in released position;

Fig. 3 is a cross section taken on line III—III of Fig. 1;

Fig. 4 is a cross section taken on line IV—IV of Fig. 1; and

Fig. 5 is a vertical section taken on line V—V of Fig. 1.

Referring to the drawings in detail, and particularly to Fig. 1, A indicates a suitable form of lock housing, in which is slidably mounted a latch bolt 2. Formed on opposite sides of the housing are spindle bearings 3 and 4, and extending through and supported in said bearings is a hollow spindle 5, on one end of which is secured a knob 6, which will hereinafter be referred to as the inner knob, and on the opposite end of which is secured a knob 7 which will hereinafter be referred to as the outer knob.

Insertable through the outer knob and into the outer end of the spindle 5 is the cylinder 8 of a suitable form of pin or plate tumbler lock, and formed on the inner end of said cylinder is a lug 9, the function of which will hereinafter be described. Drilled adjacent the inner end of the cylinder 8 is a hole 10 in which is mounted a spring 11 and a detent 12. Formed on opposite sides of the spindle, and in alignment with the hole 10, are holes 13 and 14; also formed in the knob, in alignment with the hole 14, is a hole 15

which is adapted to receive the outer end of a pin 16. This pin is mounted in the spindle, and its inner end is shouldered to limit outward movement. This shoulder is of the same diameter as the hole 10, so as to permit the pin 16 to be pushed inwardly against the detent 12 in order to permit the pin 16 to be depressed sufficiently to clear the hole 15 in the knob. In the position shown in Fig. 1, the pin 16, hereinafter to be referred to as a latch or fastener, cannot be depressed, as the shoulder or head end of the pin 16 engages the exterior surface of the cylinder 8. However, when the proper key is inserted, and the cylinder 8 rotated a half revolution, the hole 10 and the detent 12 will align with the head on the pin 16, and it may then be depressed sufficiently to permit the knob to be released and removed. The knob under normal conditions is secured against endwise removal by the pin or latch 16, and it cannot be released except by a person in possession of the proper key, as the cylinder 8 must be rotated until the detent aligns with the head of the latch 16.

The inner knob 6 is secured against removal by an identical form of latch or pin, such as shown at 16a, and it is held in latching position by a rod 18. This rod fills the inner space of the tubular spindle, but it is rotatable therein. Its outer end projects through the inner knob 6 and is provided with a thumbpiece or turnpiece 19 to permit rotation of the rod. The rod has a cross-hole 10a formed therein, and mounted therein is a spring and detent 12a (see Fig. 4). When the rod 18 is rotated a half revolution the detent will register with the head of the pin 16a and in that position the pin or latch may be depressed to release the inner knob.

The rod 18 serves another function besides that of a retainer for the spring and detent. By referring to Fig. 1, it will be noted that the sides of the rod are cut away to form a flat central piece 20, and that the inner end of the rod is provided with a lug 9a which cooperates with the lug 9 formed on the inner end of the cylinder 8. The flat member 20 is a dog actuator. That is, a dog consisting of a flat plate 22 is positioned at the rear side of the spindle; this plate is provided with two dogs 23 one on each side thereof, and these dogs are normally urged by a spring 24 into a pair of openings 25 formed in the spindle (see Fig. 2). When the dogs are in the openings the spindle is dogged against rotation, and when the spindle is dogged against rotation, retraction of the latch bolt 2 can not take place. Any attempt to rotate either the inner or outer knob

will therefore be of no avail when the dogs 23 assume the position shown in Fig. 1, as the knobs are secured to the spindle and the spindle can not rotate as it is dogged. The dogs may, however, be moved to the retracted position shown in Fig. 2 either by rotating the rod 18 a quarter revolution, by means of the turnpiece 19; or it may be rotated by means of the insertion of a key, as the insertion of a key will permit rotation of the cylinder, and such rotation will cause the lug 8 to engage the lug 9a and cause rotation of the rod, and the dog actuator or plate 20 will thus move the dogs either into or out of dogging position, and when moved to the position shown in Fig. 2 the spindle may be rotated by either knob to retract the latch bolt.

Retraction of the latch bolt is accomplished by a roll-back member 30 formed on the spindle; this engages with a pair of shoulders 31 (see Fig. 5) formed at the rear end of a retractor plate 32. This plate in turn is connected with the latch bolt 2, and that is the manner in which the latch bolt is retracted. The latch bolt is normally held in extended position by the springs 2a, and the dogs 23 are normally held in dogging position by the spring 24.

The spring actuated detents 12 and 12a serve two functions, first that of projecting the pins or latches 16 and 16a into engagement with the respective knobs, and secondly they function as yieldable stop members to position either the cylinder 8 of the key mechanism or the rod 18 which operates the dog actuator 20. When the turnpiece 19 on the rod assumes a horizontal position, the actuator 20 assumes a vertical position and the dogs 23 a dogging position. When the rod 18 is turned by the turnpiece 19 until this assumes a vertical position, the actuator 20 will assume a horizontal position, as shown in Fig. 2, and the dogs 23 will assume their retracted position where rotation of the spindle will be permitted. The holes shown at 35 and 36 in Fig. 4 are provided for the purpose of receiving the detent 12a, and thus yieldingly secure the turnpiece and the rod 18 in one position or another. The hole 13, in cooperation with the detent, yieldingly secures the cylinder 8 in locking position.

The lock shown in the present instance is

merely presented for purposes of illustration. Obviously the type of knob fastener or latch member 16, together with the spring actuated detent here shown, may be used in connection with knobs and similar mechanism on other types of locks; and while certain other features of my invention have been more or less specifically described for purposes of illustration, I wish it understood that changes may be 10 sorted to within the scope of the appended claims.

Having thus described my invention, what I claim and desire to secure by Letters Patent is:

1. In a structure of the character described, 15 a hollow spindle, a knob mounted thereon, a depressible latch member extending radially through the spindle and into the knob to secure it against removal, a rotatable member within the spindle, said member having one portion preventing depression of the latch and having a recess formed therein at another portion to permit depression of the latch, a spring actuated detent mounted in the recess, and means for rotating the rotatable member to register the recess and detent with the latch, said detent when in register with the latch maintaining the latch projected but permitting manual depression of the latch.

2. In a structure of the character described, 20 a hollow spindle, a knob mounted thereon, a depressible latch member extending radially through the spindle and into the knob to secure it against removal, a rotatable member within the spindle, said member having one portion preventing depression of the latch and having a recess formed therein at another portion to permit depression of the latch, a spring actuated detent mounted in the recess, and means for rotating the rotatable member to register the recess and detent with the latch, said detent when in register with the latch maintaining the latch projected but permitting manual depression of the latch.

3. In a structure of the character described, 25 a hollow spindle, a knob mounted thereon, a depressible latch member extending radially through the spindle and into the knob to secure it against removal, a rotatable member within the spindle, said member having one portion preventing depression of the latch and having a recess formed therein at another portion to permit depression of the latch, a spring actuated detent mounted in the recess, means for rotating the rotatable member to register the recess and detent with the latch, said detent when in register with the latch maintaining the latch projected but permitting manual depression of the latch, and a recess formed in the inner surface of the hollow spindle with which the detent is adapted to register in another position of the rotatable member, said detent yieldingly resisting rotation of the rotatable member.

WALTER R. SCHLAGE.
